UNITED STATES PATENT OFFICE.

JOHN E. MITCHELL AND DENNIS PARKS, OF ST. LOUIS, MISSOURI.

HEEL-BLANK-BUILDING MACHINE.

Application filed March 26, 1921. Serial No. 456,025.

To all whom it may concern:

Be it known that we, JOHN E. MITCHELL and DENNIS PARKS, citizens of the United States, residing in the city of St. Louis, and 5 State of Missouri, have invented new and useful Improvements in Heel-Blank-Building Machines, of which the following is a specification.

This invention relates, first, to heel-blank 10 building machines of the type described and illustrated in our co-pending application, Serial No. 432,695, filed December 23rd, 1920.

In the machine of this prior application, 15 the heel-blanks and separating members are forced upward in a log-holder in the form of a log, and successively separated from the end of the log and returned by a trough to a position within the reach of the operator. 20 In operation it was necessary for the operator to remove the heel-blanks from the trough and sometimes to separate the heel-blank from a separating member before the latter could be again used.

25 It is one of the objects of the present invention to provide for automatically separating the heel-blanks from the separating members while the log is in transit, and preferably at the rear of the machine, or at 30 a point remote from the operator.

It is a further object of the invention to return the separating members to a point within reach of the operator in regular order, and cause the separating members to 35 travel in a fixed path and to be arrested in order at a fixed point, so that the separating members will always be convenient of reach and will always occupy the same relative position with respect to the machine, thereby 40 facilitating the ease and rapidity with which they may be taken up by the operator and applied to the assembled heel-blanks.

A still further object of the invention relates to a compressible stop for arresting the 45 return movement of the heel-blanks.

A still further object of the invention relates to the provision of means for engaging and holding each heel blank as it is forced into the holder to hold the heel-blank 50 under compression or, in other words, prevent its swelling, and likewise to prevent the outermost or lowermost lift or lifts from separating from the remainder of the heel-blank.

55 The invention relates, secondly, to the employment of a novel method in the art of

heel-blank building to be followed preferably by the use of a machine as hereinafter set forth.

All of the objects and advantages attained 60 in the use of our prior machine and method are likewise attained in the use of the present machine and method, but with greater facility and in an improved degree.

In addition to the general objects outlined, 65 the invention also is concerned with various novel details of construction and combinations and operations of parts as will herein-after be described and claimed.

In the accompanying drawings, 70

Figure 1 is a view in side elevation of a machine constructed according to our invention;

Figure 2 is a view in side elevation, on an enlarged scale, of the log-holder and superimposed race-way for returning the separating members to a point within reach of the operator;

Figure 3 is a plan view of the same; 75

Figure 4 is a sectional view on line 4—4 of Figure 2;

Figure 5 is an end view of the log-holder and race-way, viewed from the right hand side of Figure 2, or from the front of the machine; and 85

Figure 6 is a broken plan view showing the end of the heel-log at the front side of the machine to illustrate the operation of the springs for engaging under the side edges of the heel-blank forced into the 90 holder to hold the same under compression.

Referring now to the drawings, the numeral 1 indicates the main frame of the machine supported by legs or standards 2 on a base 3 and in its upper portion providing inclined frame members 4. The pulley 5 driven from a belt 6, operates an eccentric rod 7 which in turn operates a throw-lever 8, such movement being under the control of the operator and effected by manipulating the foot treadle 9. The operation of the machine is exactly the same as set forth in our said pending application and need not be described more in detail. Mounted on the end of the throw-lever 8 is a slide 10 provided with an upstanding plate 11 against which the heel-blanks are built up and which, when the throw-lever 8 is moved upwardly, forces the heel-blanks into the log-holder indicated, generally, by the 105 numeral 12 in the various views where it appears. The said log-holder comprises a

breast-plate 13 and a back-plate 14 which is usually V-shaped in cross-section. The breast-plate 13 is suitably secured on the inclined frame-members 4 and the back-plate 14 is adjustably mounted by means of a bracket 15 with respect to the breast plate 13 in the same manner as described in our application aforesaid. Mounted on the upper side of the back plate 14 is the race-way 16 for discharging the heel-blanks and returning the separating members to the operator. This race-way comprises, in the preferred embodiment shown, a wooden beam 17 which is substantially the length 15 of the log-holder and which has a rounded end 18 projecting beyond the rear end of the log-holder as shown in Figure 1. The beam 17 may be secured on the back-plate 14 by cutting transverse apertures 19 there- 20 in at two or more points and then passing bolts 20 upward through apertures in the back-plate 14 and through openings in the beam entering the apertures 19 and screwing the ends of said bolts into nuts 21 inserted laterally in said apertures. As 25 shown by Figures 4 and 5, the bottom edge of the beam 17 is provided with a V-shaped groove to receive the correspondingly shaped portion of the top of the back-plate 14. The upper edge portion of the beam 17 is provided with a central longitudinally 30 extending groove 22, Figure 4, which extends from the front end of the beam 17 to and around the rear rounded end thereof. 35 Secured on the upper edge of the beam 17 and extending from the front end thereof to and around the rear rounded end 18, are two parallel metal strips 23, Figures 2 and 3, which provide between their inner op- 40 posed edges, a slot 24 which extends over but is narrower than the groove 22 in beam 17. This construction provides a bayonet groove for receiving a head 25 provided on the upper side of each of the separating 45 members 26. These separating members are of the general form illustrated in the patent of Dennis Parks, 1,381,735, dated June 14, 1921, and the special construction of separating member for use in connection 50 with the present invention forms the subject matter of a separate application for patent of Dennis Parks, Ser. No. 455,807. In the operation of the machine, the head 25 on each separating member will be forced 55 into the slot 24 as the log is pushed rearwardly by the insertion of new heel-blanks into the forward end of the log-holder, the entrance of the head in this slot being shown in Figure 4 at the bottom of the 60 figure, and which occurs at a point just before that at which the strips 23 and slot 24 take a curved path as shown more particularly in Figure 2 at the left hand end of the figure. As each separating member 65 passes into the curved portion of the slot

24, the plate 27 or separating element proper, will be turned out of engagement with the heel-blank 28 as the breast of the latter is still in engagement with the surface of the breast-plate 13, and in this way the 70 separating member is automatically disengaged from the heel-blank. In the further movement of the separating member and heel-blank, the latter will be discharged from the rear end of the log-holder as 75 shown in Figure 2, while the separating member will continue to pass around the curved end 18 of the race-way. When it passes over this curved portion it then enters upon the downwardly inclined part, or 80 upper side, of the race-way and slides by gravity down the same to the forward end of the race-way. In order to arrest the movement of the separating members, we provide the following construction: 85

The forward end of the beam 17 is recessed vertically and longitudinally as indicated at 29 and 30 respectively, at the right of Figure 2. Numeral 31 indicates a stop plate which is bifurcated in its upper 90 edge portion to provide a slot 32, Figure 5, and is provided on opposite sides of said slot with forwardly projecting fingers 33. On its rear face the plate 31 is provided with a central rectangular rib 34 which is 95 slidably mounted in the recess 29 and is apertured from its lower end upward a certain distance to receive a coil spring 35, the lower end of which rests upon the bottom of the recess 29. Plate 31 is further provided 100 towards its upper end with a recess 36 and an aperture 37 leading from said recess and extending through the rib 34 through which recess and aperture extends a rod 38 into the recess 30 where its rear end is pivotally 105 mounted as indicated at 39. Surrounding the forward end of the rod 38 and seated in the recess 36 is a coil spring 40 which is held under tension by a nut 41 screwed on the end of the rod 38. The upper end of 110 the plate 31 projects above the upper side of the race-way 16, as shown in Figures 1 and 2, and as indicated at 42, and this projecting portion provides a stop against which the separating members 26 engage 115 when they slide down the race-way 16. The slot 32 in the plate 31 corresponds with the slot 24 of the race-way, and to remove a separating member 26 the operator presses down on fingers 33 to remove the projecting portion 42 below the lower edge of the plate 27 of the separator and the latter can be slid out of the race-way, its head 25 passing through the slot 32 in the stop-plate. 120

Referring particularly to Figures 2, 3, 5 and 6 we will now describe the means for holding under compression the lifts of a fresh heel-blank forced into, or partly into, the log-holder to maintain the heel-blanks 130

of uniform size by preventing the swelling of the lifts due to the presence of the moisture in the paste, and also to prevent one or more of the lifts from falling off or being 5 knocked off of the heel-blank in the portion projecting from the entrance end of the log-holder.

In the operation of the machine of the application previously referred to, it was 10 found that the lifts at the front or projecting end of the heel-blank would frequently become displaced and would fall off and that due to swelling, there would be some irregularity in the heights of the 15 heel-blanks. This objection we aim to overcome by means of the construction shown particularly in the figures referred to.

Referring to these figures, the numerals 43 indicate two leaf springs which are 20 cured at their rear ends to opposite sides of the bracket 15 as indicated at 44 in Figure 2. These springs extend along and bow out slightly from opposite sides of the breast plate 13 and project beyond the front 25 end of the back plate 14 as shown in Figures 2 and 6, the projecting ends being formed with shoulders 45 to engage behind the heel-blank at the side edges thereof, as indicated in said Figure 6. The shoulders 30 45 are provided with heads, the inner sides of which are rounded to diverge outwardly so as to facilitate the entrance of the heel-blanks between the springs and at the same time, force the springs apart so that when 35 the heel-blank has passed beyond the shoulders 45, the springs will snap in behind the heel-blank.

From the above description, it will be seen that as the heel-blanks are forced into 40 the log-holder 12 they will be held under compression by frictional engagement with the side walls of the holder and by the engagement of the shoulders of the springs 43 with the opposite edge portion of the 45 last heel-blank inserted. This applies, of course, to the entire column of heel-blanks inserted in the holder and as the latter is filled with the heel-blanks the said heel-blanks will be separated from the separating 50 members 26 as the position of the latter, with reference to the heel-blank, is changed by the separating member taking the curved path at the end of the race-way, as shown at the left in Figure 2, the separating 55 members continuing to pass around the curved end of the race-way until the top of the latter is reached, when they in turn slide down the race-way and are arrested by engagement of the forward separating 60 member with the projecting portion 42 of the plate 31. When the operator presses down on the fingers 33 to lower the plate so that a separating member can be removed from the race-way, the rod 38 will turn on 65 the pivot 39 and the said plate will slide in

engagement with the end of the race-way or block 17, this movement being permitted by the yielding of the spring 40. The tension of this spring can be adjusted by means of the nut 41. When pressure is 70 released on fingers 33 the coil spring 35 returns the plate 31 to its normal or projecting position shown in Figures 1 and 2.

We claim:

1. The method of successively separating heel-blanks and separating members therefor temporarily maintained in column formation, which consists in continuously forcing the separating members at the end of the column into a path diverging from that 80 of the heel-blanks, and in the same operation moving the heel-blank adjacent to the separating member to an unsupported position whereby it may fall away from the column by gravity. 85

2. The method of successively separating heel-blanks and separating members therefor temporarily maintained in column formation, which consists in successively forcing the separating members at the end of the 90 column into a path diverging from that of the heel-blanks while the latter are maintained in a relatively fixed path, and in the same operation moved in order to an unsupported position whereby they may successively fall away from the column by gravity. 95

3. The method of successively separating heel-blanks and separating members therefor temporarily maintained in column formation, which consists in continuously forcing the separating members and heel-blanks through a log-holder in a relatively straight path, and successively forcing the separating members at the end of the column into a path diverging from that of the straight 100 path and simultaneously causing the heel-blank adjacent to the separating member to continue in said straight path to an unsupported position whereby it may be discharged from the holder. 110

4. In the art of heel building, the method which consists in forming a column of heel-blanks and interposed separators by successively forcing in alternation a heel-blank and a separator through a zone of frictional resistance, successively forcing the separating members at the end of the column into a path diverging from that of the heel-blanks, whereby to detach each separator from its heel-blank, and successively returning the 115 separators to the region of the initial operation. 120

5. In the art of heel building, the method which consists in forming a column of heel-blanks and interposed separators by successively forcing in alternation a heel-blank and a separator through a zone of frictional resistance, successively forcing the separating members at the end of the column into a path diverging from that of the heel- 125 130

- blanks whereby to detach the separator from the heel-blank and causing the separators to follow a fixed path terminating in the region of the initial operation.
- 5 6. In the art of heel building, the method which consists in forming a column of heel-blanks and interposed separators by successively forcing in alternation a heel-blank and a separator in an upward direction 10 through a zone of frictional resistance, successively forcing the separating members at the end of the column into a path diverging from that of the heel-blanks, whereby to detach each separator from its heel-blank, and 15 causing said separators to follow a fixed path and to be returned by gravity through a portion of said path to the region of the initial operation.
7. In the art of heel building, the method 20 which consists in forming a column of heel-blanks and interposed separators by successively forcing in alternation a heel-blank and a separator through a log-holder, discharging the heel-blanks in order from the 25 log-holder at the remote end thereof in each successive movement of the column and separately returning the separators to the region of the initial operation.
8. In the art of heel building, the method 30 which consists in forming a column of heel-blanks and interposed separators by successively forcing in alternation a heel-blank and a separator through a log-holder, successively forcing the separators at the end of 35 the holder into a path diverging from that of the heel-blanks, discharging the heel-blanks in order from the holder at such point of divergence in each successive movement of the column and returning the separators 40 to the region of the initial operation.
9. In a machine of the class described, the combination of a holder for a series of heel-blanks and separators in column formation, means for forcing successive blanks 45 and separators into the holder at one end thereof, a lateral extension at the remote end of the holder and means for guiding the separators in order over said lateral extension.
- 50 10. In a machine of the class described, the combination of a holder for a series of heel-blanks and separators in column formation, means for forcing successive blanks and separators into the holder at one end 55 thereof, a race-way having a curved portion at the remote end of said holder and an inclined portion terminating in the region of the initial operation, and means for guiding the separators over said curved portion to 60 said inclined portion whereby the separators will slide by gravity to the termination of said race-way.
11. In a machine of the class described, the combination of a holder for a series of 65 heel-blanks and separators in column for-

mation, means for forcing successive blanks and separators into the holder at one end thereof, a race-way having a portion diverging from the remote end of the holder and an inclined portion terminating at the region 70 of the initial operation, a retaining guide extending throughout the length of said race-way and means on each of said separators for engaging said retaining guide whereby the separators in order will move 75 away from said holder to said inclined portion and return by gravity to the terminus of said race-way.

12. In a machine of the class described, the combination of an upwardly inclined 80 holder for a series of heel-blanks and separators in column formation, means for forcing the blanks and separators successively into the holder at the lower end thereof, a slotted race-way having a curved portion 85 diverging from the remote end of said holder and an inclined portion terminating at the lower end of said holder and a head on each separator for engaging in the slot of said race-way whereby the separators will 90 be guided about the curved end of said race-way to said inclined portion and will slide down the latter to its terminus at the lower end of the holder.

13. In a machine of the class described, 95 the combination of an upwardly inclined holder for a series of heel-blanks and separators in column formation, means for forcing the blanks and separators successively into the holder at the lower end thereof, a 100 race-way having a diverging portion at the remote end of said holder and an inclined portion terminating at the lower end thereof, a guide extending throughout said race-way, means on each separator for engaging 105 said guide whereby the separators will be guided to said inclined portion and slide by gravity down the latter, and a movable stop at the lower end of said race-way for arresting the movement of said separators. 110

14. In a machine of the class described, the combination of an upwardly inclined holder for a series of heel-blanks and separators in column formation, means for forcing the blanks and separators successively 115 into the holder at the lower end thereof, a race-way having a diverging portion at the remote end of said holder and an inclined portion terminating at the lower end thereof, a guide extending throughout said race-way, means on each separator for engaging 120 said guide whereby the separators will be guided to said inclined portion and slide by gravity down the latter, and a depressible stop at the lower end of said race-way for 125 arresting the movement of said separators.

15. In a machine of the class described, the combination of a log-holder, a plurality 130 of spring members having outwardly directed shouldered ends projecting beyond

that end of the holder constituting the mouth thereof and positioned in the path of movement of heel-blanks to be forced into said holder, and means for forcing heel-blanks between said spring members, to separate the same, and into said holder, whereby as each heel-blank, in order, passes beyond said shouldered ends, the latter will automatically snap over the heel-blank and hold the same, or the lifts thereof, from 10 backward movement.

5 In testimony whereof, we have hereunto set our hands.

JOHN E. MITCHELL.
DENNIS PARKS.
